Primary Examiner—Raphael Barkai
Assistant Examiner—Randall H. Gholson(57) **CLAIM**

The ornamental design of a hexagonal SAE and metric socket, as shown and described.

DESCRIPTION

FIG. 1 is a front perspective view of a hexagonal SAE and metric socket of my new design;
FIG. 2 is a top plan view thereof;
FIG. 3 is a bottom plan view thereof;
FIG. 4 is a front elevational view thereof;
FIG. 5 is a rear elevational view thereof;
FIG. 6 is a side elevational view thereof, the opposite side elevational view being a mirror image thereof;
FIG. 7 is a reduced scale section view taken along the line 7-7 of FIG. 2;
FIG. 8 is a perspective view of a modification of the hexagonal SAE and metric sockets of FIG. 1;
FIG. 9 is a top plan view of FIG. 8; and
FIG. 10 is a bottom plan view of FIG. 8;
FIG. 11 is a front elevational view of FIG. 8;
FIG. 12 is a rear elevational view of FIG. 8;
FIG. 13 is a side elevational view of FIG. 8, the opposite side elevational view being a mirror image thereof;
FIG. 14 is a reduced scale sectional view taken along the line 14—14 of FIG. 9;
FIG. 15 is an enlarged top plan view of the section 15 of FIG. 2; and,
FIG. 16 is an enlarged top plan view of the section 16 of FIG. 9.
